CLAIM

The ornamental design for an electric motor driven angle head nutrunner, as shown and described.

DESCRIPTION

FIG. 1 is a top view of an electric motor driven angle head nutrunner showing our design;

FIG. 2 is a left side elevational view thereof;

FIG. 3 is a front elevational view thereof;

FIG. 4 is a rear elevational view thereof; and,

FIG. 5 is a bottom view thereof.

The right side elevation is a mirror image of FIG. 2.
